UNITED STATES PATENT OFFICE.

ROBERT A. FORESMAN, OF MOORES, PENNSYLVANIA, ASSIGNOR TO WESTINGHOUSE ELECTRIC & MANUFACTURING COMPANY, A CORPORATION OF PENNSYLVANIA.

UNDERFEED STOKER.

Application filed January 26, 1925. Serial No. 4,727.

My invention relates to underfeed stokers of the type embodying alternate fuel retorts and intervening tuyère banks, and it has for its object to provide fuel feeding means for a stoker of the character designated 5 which shall introduce fuel thereinto in a substantially unbroken sheet across the entire stoker width, said sheet being of relatively great thickness where entering the 10 retorts and of relatively little thickness where passing over the front ends of the tuyère banks.

A further object of my invention is to provide apparatus for suitably supporting 15 the front wall and for introducing air across the entire stoker width when employing fuel feeding means of the character above described.

In the accompanying drawing, Fig. 1 is a 20 view, partially in section and partially in elevation, illustrating an underfeed stoker constructed in accordance with a preferred form of my invention; Fig. 2 is a plan view, partially in section, of the structure shown 25 in Fig. 1, being taken on the plane II—II thereof; and Fig. 3 is a transverse section, of the ram structure employed in the device of Fig. 1, being taken on the line III—III.

In the construction of underfeed stokers, 30 it has been the usual custom to provide a fuel hopper across the stoker front with distant rams, generally of circular cross section, operating in front of the respective retorts, whereby fuel is introduced into the retorts and forced up out of the latter and over the adjacent tuyère banks. Each tuyère bank has been capped by a locking tuyère 35 merging with the front wall structure.

In accordance with the present invention, 40 I provide lateral wings on rams of the aforementioned type, said wings extending into proximity with each other and I round off the upper end of the tuyère bank in such manner as to provide a fuel admitting opening in front of each tuyère bank, fuel being forced thereinto by said wings. In this manner, I introduce fuel into the furnace in a 45 substantially unbroken sheet across the entire stoker width, said sheet being relatively 50 thick at the respective retorts and relatively thin over the respective tuyère banks.

Referring to the drawing for a more detailed understanding of my invention, I show retorts at 10—10 in Figs. 1 and 2, said 55 retorts being separated by tuyère banks 11—

11 of any desired type and as well-known and understood in the art.

At the front of the furnace, the respective tuyère banks 11—11 are flattened off and brought to a prow-shaped point as indicated 60 at 12—12, rather than merging into the front wall as has been the common practice hitherto.

The front wall structure 13 is carried by a pair of I-beams 14 and 15 extending substantially across the entire stoker front and carrying suitable interlocking castings 16 and 17, the former being provided with corrugations in the lower face thereof and the latter defining the upper boundary of the 70 fuel admitting opening to the furnace. The ends of the corrugations on the members 16 provide air openings at 18 through which air may be admitted across the entire furnace width from any suitable source, said 75 air preferably being supplied under pressure through a conduit such as that defined by the I-beams 14 and 15, although any other desired air supplying structure may be employed.

Coaxially disposed in front of each retort 10 is a ram member 19, the cross sectional shape thereof being clearly shown in Fig. 3. Briefly speaking, each of these rams may be 80 be considered as comprising a body having two portions which are, respectively, rectangular and semi-circular in cross section, the semi-circular portion being below the rectangular portion, and narrower than said rectangular portion. Each ram 19 is mounted 85 for reciprocation in a suitably shaped ram box and the respective sizes are such that said ram boxes are in abutting relation 90 as indicated at 20 in Fig. 3. The rams 19 are mounted for actuation in the usual manner as by a crank shaft 21. Fuel is supplied 95 to the rams 19 as from a hopper 21.

Having thus described the arrangement of the structure embodying my invention, the operation thereof is as follows: Upon 100 providing the hopper 21 with fuel and reciprocating the rams 19—19, the fuel is passed in to the furnace in a substantially unbroken sheet across the entire furnace width. The relatively thick portions of the 105 rams 19—19 being disposed directly in front of the respective retorts, it follows that fuel is introduced at a relatively rapid rate into the retorts themselves, whereas it is introduced at a lesser rate directly over the ends 110

of the tuyère banks by the lateral lugs or ears upon the respective rams. Owing to the peculiar configuration of the upper ends of the tuyère banks, there is little or no clogging or eddying in the fuel stream, but it passes into the furnace and over the stoker structure in a smooth and desirable manner as is conducive to best combustion results. All portions of the fuel bed are caused to move progressively onwardly so that all portions of the fuel coke at an even rate, resulting in an exceptionally even and desirable fire.

By regulating the amount of air supplied to the openings 18, the activity of combustion at the front end may be controlled with marked facility.

While I have shown my invention in but one form, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:

1. In an underfeed stoker, the combination with means providing rearwardly extending retorts and intervening tuyère banks, of a continuous fuel hopper across the front of said stoker, a ram box for each retort and disposed beneath the hopper, a fuel ram in each ram box and centrally located in front of each retort, each fuel ram being provided with flanking portions extending approximately to the center lines of the adjacent tuyère banks, respectively, and means for reciprocating said rams, whereby fuel is introduced into each retort and over the adjacent tuyère banks.

2. The combination with an underfeed stoker embodying alternate retorts and tuyère banks, of ram means for introducing fuel at the front thereof, in the form of a plurality of adjacent channels, each channel being relatively thick at the center thereof and relatively thin at the lateral edges thereof, said channels abutting in planes substantially coincident with the longitudinal central planes of said tuyère banks.

3. In a fuel feeding structure for an underfeed stoker embodying a plurality of fuel

retorts with intervening tuyère banks, a plurality of laterally abutting ram boxes each formed in cross section with a laterally extending rectangular portion and a semi-circular portion beneath the rectangular portion, rams of corresponding shape in the ram boxes, and means for reciprocating the rams, the rectangular portions of said rams being adapted to introduce fuel into the upper portions of the respective retorts and over the adjacent tuyère banks and said semi-cylindrical portions being adapted to introduce fuel into the lower portions of the respective retorts.

4. In a furnace, the combination of an underfeed stoker including alternate retorts and tuyère banks; ram means for introducing fuel onto said stoker in a substantially unbroken stream extending across the entire width thereof; the stream of fuel having greater effective depth in front of said retorts than in front of said tuyère banks; the construction and arrangement of the stoker and ram means being such that the forward ends of the tuyère banks are spaced rearwardly of the effective working portions of the ram means when said ram means are in their extreme forward position.

5. In a furnace, the combination of an underfeed stoker comprising alternate retorts and tuyère banks, said tuyère banks being flattened at their fuel receiving ends, a wall for said furnace extending across the front thereof and having its lower portion disposed above and spaced from the flattened ends of the tuyère banks so as to provide an unrestricted fuel feeding opening for the furnace, and ram means for introducing fuel onto said stoker in a substantially unbroken stream extending across the entire width thereof; the stream of fuel having greater effective depth in front of said retorts than in front of said tuyère banks; the construction and arrangement of the stoker and ram means being such that the forward ends of the tuyère banks are spaced rearwardly of the effective working portions of the ram means when said ram means are in their extreme forward positions.

In testimony whereof, I have hereunto subscribed my name this sixteenth day of January, 1925.

ROBERT A. FORESMAN.
